ALFRED ROESCH, OF BROOKLYN, NEW YORK, ASSIGNOR TO CHARLES J. TAGLIABUE
MANUFACTURING CO., OF BROOKLYN, NEW YORK, A CORPORATION OF NEW YORK.

BLOOD-PRESSURE GAGE.

1,282,632.

Specification of Letters Patent. Patented Oct. 22, 1918.

Application filed June 30, 1917. Serial No. 178,022.

To all whom it may concern:

Be it known that I, ALFRED ROESCH, a citizen of the United States, and resident of the borough of Brooklyn, county of Kings, city 5 and State of New York, have invented certain new and useful Improvements in Blood-Pressure Gages, of which the following is a specification.

My invention relates to gages of the type 10 commonly known as blood pressure gages and has for its object to produce an instrument which is simple in construction, cheap and easy to produce and in which the necessity for particularly accurate work during 15 manufacture is avoided. My invention further contemplates the provision of an instrument of the indicated type which is extremely sensitive, even to a small fraction of a millimeter of mercury, which will produce 20 and repeat accurate readings and in which inaccuracies in operation are immediately indicated. My invention will be fully described hereinafter and the features of 25 novelty will be pointed out in the appended claims.

In the accompanying drawings, which show an example of my improvement, Figure 1 is a front elevation partly in section; Fig. 2 is a detail view on an enlarged 30 scale and Fig. 3 is a detail side view also on an enlarged scale.

As shown in the illustrated example the instrument comprises a casing 5 constructed of suitable material and preferably in the 35 form of a quadrant; that is the side walls 5^a of said casing diverge upwardly and are connected by a curved top wall 5^b, the front wall 5^c and rear wall 5^d being substantially parallel with each other. The casing 5 is secured 40 to and extends upwardly from a lower section 6 which is preferably cylindrical in form, said casing 5 at its lower end being formed with an opening located in registry with an opening in the top of the section 6 whereby communication between the interiors of the casing 5 and section 6 is established. The lower end of the section 6 is closed by means of a closure 7 which may be 45 frictionally held in position or otherwise secured as may be desired and which carries an upright yoke 8, the latter preferably forming an integral part of said closure.

The closure 7 also supports a bellows 9 of any well known or suitable construction and 50 secured in position, for instance, by means

of a screw-threaded neck 10 which screws into a screw-threaded opening in the closure 7 and is of such a length as to project somewhat beyond the same. The projecting portion of the neck 10 may be used as a means 60 whereby a nipple 11 is operatively combined with the instrument, it being understood that the neck 10 is tubular, thus establishing communication between the interior of the bellows 9 and the nipple 11. The arrangement may further include a screw-threaded stem 12 having its one end suitably secured to the bellows 9 and extending through the neck 10 into the nipple 11. The stem 12 carries a nut 13 which co-operates, for instance, 65 with the inner end of the nipple 11 to limit the expansion of the bellows and which may be adjusted upon said stem to vary the point at which said expansion is arrested.

The yoke 8 supports a frame 14 having upright members 15, 15^a and 15^b spaced from each other as shown in Fig. 2. An indicating hand 16 is carried by a spindle 17 rotatably mounted between the members 15 and 15^a, the hand 16 being formed at its 70 lower end with an extension 18 extending at an angle to said hand and carrying a counter weight 19. The hand 16 is further provided at a lower end with a member 20 extending at an angle in a direction opposite 75 to that of the arm 18 and arranged in surface engagement with an adjustable member 21. The latter extends transversely across the lower end of the hand 16 and is provided with a slot 22 for the accommodation of the 80 spindle 17 and of a screw 23 whereby the members 20 and 21 are operatively connected to each other. A link 24 has its one end pivotally connected at 25 with the member 21 and at its other end is provided with a 85 slot 26 through which a pivot pin 27 passes loosely. The latter is carried by an arm 28 and constitutes a loose pivotal connection between said link 24 and the arm 28 which in the illustrated example forms part of and 90 inclines upwardly from a plate or the like 95 secured to the upper end of the bellows 9 in any suitable manner as by means of a screw or bolt 30. The free end of the indicating hand is arranged in a co-operative relation to a scale 31 produced upon a scale plate 32 secured in proper position in the 100 casing 5 in any suitable manner as by screws 33. The scale as shown is graduated in millimeters of mercury and in the illustrated ex- 105 110

ample ranges from 60 to 260 millimeters of mercury as shown in Fig. 1. In its position of rest the indicating hand 16 is in registry with the scale indication 60 and rests against 5 a stud or stop 34 located at the proper point upon the scale plate 32, said hand 16 being held in this position by the action of the counter-weight 19.

The instrument further includes a correction or zero hand 35 which in combination 10 with a zero indication or other designation 36 produced on the scale plate 32, indicates whether the instrument is true and its readings are correct or not. The hand 35 is carried by a spindle 37 journaled between the members 15^a and 15^b of the frame 14 at a point above the axis of the spindle 17. The hand 35 is formed at its lower end with a member 38 which extends at an angle to said 15 hand and in the illustrated example is continued in the form of an extension 39 carrying a counter-weight 40. A link 41 has its one end pivotally connected at 42 with the member 38 and its other end pivotally 20 connected at 43 with an arm 44 similar to the arm 28 and likewise forming part of and inclining upwardly from the plate or the like 29. In the preferred construction 25 the arms 28 and 44 are located at opposite edges of the plate or the like 29 and incline upwardly in opposite directions from opposite ends of said plate so as to appear to intersect each other when viewed from the front or rear.

35 In practice, the instrument being properly adjusted and at rest with the bellows in proper coöperative condition, the indicating hand 16 rests against the stud 34 with its free end in registry with the scale indication 40 60, being maintained in this position by the counter-weight 19. In this condition of the instrument the pivot 27 is near the lower end or at an intermediate point of the slot 26 of the link 24 as shown in Figs. 1 45 and 3. The zero or correction hand 35 being in fixed connection with the bellows 9 through the medium of the link 41 is held thereby in registry with the designation 36 thus indicating that the instrument is true 50 and in proper working condition. The nipple 11 is connected by means of a rubber tubing or the like with the usual blood pressure testing arrangement, it being understood that the connection with the human being may be of any usual type.

55 As the bellows 9 expand under inflation, as the instrument is operatively used, an upward pressure is immediately exerted upon the link 41 which is communicated to the member 38 and causes the zero hand 35 to swing away from the designation 36 toward the left in the illustrated example. The expansion of the bellows 9 also causes 60 the pivot 27 to concurrently move upward 65 in the slot 26 of the link 24 without, how-

ever, affecting said link. If the expansive movement of the bellows is sufficient to bring the pivot 27 to the upper end of the slot and continues beyond this point, or in other words, if the exerted pressure is greater than 70 60 m. m. of mercury, said pivot 27 will exert an upward pressure upon the link 24. This pressure will be communicated to the member 21, which being in rigid connection with the indicating hand 16 will thus cause the 75 latter to swing along the scale 31 toward the right in the illustrated example. As the pressure in the bellows 9 fluctuates, or increases and decreases, the hand 16 will move correspondingly backward and forward along the scale 31 thus indicating the pressure of the blood and the pulsations. The movement of the hand 16 from any position on the scale between 60 and 260 toward the left is caused by the action of the 80 counter-weight 19. In other words said counter-weight causes the link 24 to follow any downward movement of the pivot 27 due to a contraction of the bellows. This operation continues until the pressure becomes less than 60 m. m. of mercury whereupon the hand 16 is again supported by the stud 34 while the pivot 27 moves down in the slot 26 and relatively to the link 24 as the bellows continues to move toward its 85 initial position. As the bellows contracts the zero or correction hand 35 will swing back toward the designation 36 and, as long as the instrument is in correct working order, will register with this designation when the 90 bellows has reached its normal position. If the bellows has become stretched or expanded from continuous use the hand 35 will show this by not coming back to the designation 36 in the final position of said 95 bellows.

100 In this case the instrument will have to be re-adjusted or otherwise the extent of error indicated by the zero hand 35 will have to be taken into consideration in reading the instrument on the scale 31.

110 In the preferred arrangement the distance between the pivotal connection 42 and the spindle 37 is approximately twice as great as the distance between the pivotal connection 25 and the spindle 17. With this construction the indicating hand 16 will swing in an arc approximately twice as great as the arc in which the hand 35 swings in any given operation of the instrument; in other 115 words, when the indicating hand moves 90 degrees the zero hand will move about 45 degrees.

120 The connection 25 between the link 24 and the indicating hand 16 may be adjusted 125 by shifting the adjusting member 21 relatively to the member 20 whereby a proper and accurate travel of said hand between the designations 60 and 260 on the scale 31 is always assured. By bending the arms 28 130

and 44 up or down the position of rest of the hands 16 and 35 may be adjusted so as to properly register with the point 60 on the scale 31 and the designation 36 respectively.

All connections and joints may be relatively loose so that the possibility of binding or sticking of the parts is reduced to a minimum; all lost motion in said connection 10 and joints is taken up by the counterweights 19 and 40. This absence of any tendency of the parts to bind makes the instrument very sensitive and very responsive to the slightest movement of the bellows in 15 either direction.

My improved instrument is very simple in construction and efficient in operation and may at all times be relied upon to give accurate readings.

20 Various changes in the specific form shown and described may be made within the scope of the claims without departing from the spirit of my invention.

I claim:

25 1. A blood pressure gage comprising indicating mechanism, means whereby the operative condition of said indicating mechanism is indicated and devices connected with said indicating mechanism and said means, 30 said devices being adjustable independently of each other whereby the initial positions of said indicating mechanism and said means may be varied.

2. A blood pressure gage comprising a 35 scale, an indicating hand coöperating with said scale, means for actuating said indicating hand and means controlled by said actuating means and actuated thereby coincidentally with said indicating hand and operating 40 independently of said scale whereby the operative condition of said actuating means is indicated.

3. A blood pressure gage comprising a scale, an indicating hand coöperating with 45 said scale, a bellows operatively connected with said indicating hand for actuating same, and means controlled by said bellows and actuated thereby coincidentally with said indicating hand and operating independently of said scale whereby the operative condition of said bellows is indicated.

4. A blood pressure gage comprising a scale, an indicating hand coöperating with said scale, a bellows operatively connected 55 with said indicating hand, a correction hand operatively connected with said bellows and actuated coincidentally with said indicating hand and a fixed designation independent of said scale coöperating with said correction 60 hand to indicate the operative condition of said bellows.

5. A blood pressure gage comprising a scale, an indicating hand coöperating therewith, a correction hand, a bellows, and members connected respectively with said indi-

cating and correction hands whereby both hands are coincidentally actuated, said members being each adjustably connected with said bellows.

6. A blood pressure gage comprising a 70 lower section, a casing of approximately quadrant form diverging upwardly from said section, a scale plate in said casing having a scale thereon, an indicating hand co-operating with said scale, actuating means 75 within said lower section operatively connected with said indicating hand, a correction hand within said casing, a connection from said actuating means to said correction hand and a fixed designation on said scale 80 plate independent of the scale thereon and co-operating with said correction hand to indicate the operative condition of said actuating means.

7. A blood pressure gage comprising a 85 casing, a scale within said casing, an indicating hand coöperating with said scale, means movable in one direction for actuating said hand relatively to said scale in one 90 direction, a link connected with said indicating hand and adjustably connected with said actuating means whereby the initial position of said hand relatively to said scale may be adjusted, and means for causing said hand to follow a movement of said actuating 95 means in another direction.

8. A blood pressure gage comprising a casing, a scale within said casing, an indicating hand coöperating with said scale, actuating means within said casing, a link 100 adjustably connected with said actuating means and adjustably connected with said hand whereby the latter is operated in one direction and a counterweight carried by said adjustable connecting means whereby 105 said hand is operated in the opposite direction.

9. A blood pressure gage comprising a casing, a scale within said casing, an indicating hand coöperating with said scale, 110 actuating means within said casing, a member adjustably connected with said hand, a link pivotally connected at one end with said adjustable member and having a slot at its other end, an arm carried by said actuating 115 means, a pivot member movable in said slot whereby said arm and said link are loosely connected with each other and a counterweight carried by said hand for moving it in a direction opposite to its operation by 120 said actuating means.

10. A blood pressure gage comprising a casing, a scale plate therein having a scale produced on its surface, an indicating hand in said casing coöperating with said scale, 125 a counterweight carried by said hand for moving it in one direction, a member adjustably connected with said hand, actuating means within said casing, a link pivotally connected at one end with said adjustable 130

member and having a slot at its other end, an arm adjustably mounted upon said actuating means, a pivot member movable in said slot whereby said link and arm are 5 loosely connected and said indicating hand is operated in the opposite direction, a correction hand in said casing, a counterweight carried by said correction hand for moving it in one direction, a second arm adjustably 10 mounted upon said actuating means, a link pivotally connected with said correction hand and said second arm whereby said correction hand is operated in the opposite direction and a fixed designation on said scale 15 plate coöperating with said correction hand to indicate the operative condition of said actuating means.

11. A blood pressure gage comprising a casing, a scale plate in said casing having a 20 scale and a fixed designation independent of said scale produced on its surface, actuating means in said casing, an indicating hand coöperating with said scale, a correction hand coöperating with said fixed designation, and 25 connections from said two hands to said actuating means whereby said two hands are

coincidentally actuated and moved in opposite directions to indicate respectively the pressure exerted by said actuating means and its operative condition. 30

12. A blood pressure gage comprising a casing, a scale plate therein having a scale produced upon its surface, an indicating hand in said casing coöperating with said scale, a bellows for actuating said hand, an 35 arm carried by said bellows and inclined upwardly from a face thereof, a link pivotally connected with said hand and with said arm, the inclination of the latter being adjustable to different fixed positions relatively to said 40 face of the bellows to adjust the initial position of said hand relatively to said scale.

13. A blood pressure gage comprising an indicating hand, a correction hand, said two hands being movable about a common axis, 45 and means whereby said two hands are coincidentally actuated to indicate respectively the pressure and the operative condition of the gage.

In testimony whereof I have hereunto set 50 my hand.

ALFRED ROESCH.
